DOSING MEANS FOR LIQUID SYSTEMS

Chauncey B. Oliver, Blue Diamond, Nev., assignor to
Tested Appliance Company, Chicago, Ill., a corporation
of Nevada

Application March 1, 1951, Serial No. 213,407

22 Claims. (Cl. 210—31)

This invention relates broadly to liquid supply systems requiring periodic dosages of a treating liquid, and it relates more particularly to improvements and innovations in apparatus for dosing a liquid supply or distribution system with a treating liquid in response to a release or reduction in pressure on the liquid in the supply system, such apparatus being characterized by its positive and automatic type of operation and the absence of valves, check valves and moving parts.

One particular application of the present invention is to water supply or distribution systems which include a pressure supply tank or receptacle wherein air pressure in or communicating with the receptacle serves to force the water through the system. The apparatus of the present invention is designed to dose such a water supply or distribution system with a solution of chlorine or other treating liquid when the pressure on the water drops or is released prior to refilling the receptacle.

While for purposes of illustration and a specific disclosure the invention will be described in connection with water supply or distribution systems which requires periodic dosing with chlorine solution, it will be understood that the invention is broadly applicable to any liquid supply or distribution system wherein the liquid to be distributed or supplied requires periodic dosing with a treating liquid of some type.

The dosing apparatus of the present invention has been applied successfully to the water systems of railway passenger cars. This particular type of installation takes full advantage of certain unique features of the dosing apparatus. The fact that the dosing apparatus of my invention may be made of a rugged and simple construction and completely independent of any moving parts makes it particularly useful in connection with the water system of a railroad car where the requirements are exacting in respect to ruggedness, long-life, simplicity, low maintenance, long periods between refillings and dependability in performance. Another requirement of such a water distribution system is that the dosing apparatus therefor be of an automatically operating type so that each time the water supply tank of the railroad car is refilled by existing crews following established procedures and schedules, the proper dosage of chlorine solution will be introduced. One of the unique features of the present invention is that the dosage apparatus provided thereby may be installed on existing liquid supply or distribution systems without requiring alteration in the existing setup.

An important object of the invention is a dosing apparatus for introducing doses of a treating liquid into a liquid distribution system, which apparatus includes a closed container for holding a supply of the treating liquid, a closed dosage chamber disposed in gravity feed communication with the container, and means providing direct communication between the top of the dosage chamber and the top of the supply container.

Another important object of the invention is a dosing apparatus for introducing doses of one liquid into a liquid

2

supply or distribution system in response to release or reduction in the pressure maintained on the liquid within in said supply or distribution system.

Another important object of the invention is an automatically operating dosage apparatus which is free of moving parts and which functions automatically to introduce a dose of a treating liquid into a liquid supply or distribution tank or system in response to a differential or reduction in gas pressure maintained on the liquid in such a tank or system.

A more specific object of the invention is an apparatus for dosing a water supply or distribution system with a dose of chlorine solution or other liquid in response to variation or drop in the pressure of an air pressure head which serves to move the water through the system.

Still another object of the invention is a dosing apparatus which does not require any moving part and which may be connected with the compressed air pressure chamber of a water system, with the dosing apparatus operating automatically to charge a dose of chlorine or other solution into the water system in response to a drop or reduction in pressure, and more particularly in response to release and re-establishment of the air pressure coincident with the refilling of a water supply tank.

Certain other objects of the invention will, in part, be obvious and will, in part, appear hereinafter.

For a more complete understanding of the nature and scope of the invention, reference may now be had to the following detailed description thereof taken in connection with the accompanying drawings, wherein:

Fig. 1 contains a vertical sectional view through dosing apparatus forming one embodiment of the invention and shows the embodiment interconnected with a water distribution or supply system shown in elevation except where broken away;

Fig. 2 is a vertical sectional view through a dosage device which forms another embodiment of the invention; and

Figs. 3 and 4 are diagrammatic views showing two additional embodiments of the invention.

In Fig. 1 a water supply tank or receptacle is indicated at 5 for supplying water to a distribution system which is indicated generally at 6. The system 6 is supplied from the receptacle 5 by a main or header 7 which leads from the bottom of the receptacle. As one specific illustration, the receptacle 5 may be the water supply tank on a railroad passenger car while the distribution system 6 may represent the water supply system of the car. It will be understood that the water system of a railroad passenger car has been mentioned merely as being illustrative and that the invention is applicable to water or other liquid systems broadly wherein there is a supply tank which is maintained under pressure which varies or is released periodically.

In addition to the outlet connection for the main 7, the receptacle 5 is provided at the top with three additional connections. One of these connections is indicated at 8 and this is the water feed or supply connection. The bottom end of this connection 8 projects into the receptacle 5 and terminates at the high water level which is indicated at 10. This arrangement insures the reservation of a freeboard or pressure head space 11 in the top of the receptacle 5 each time it is filled up. The water supply line 8 is provided with a suitable valve 12 for closing and opening the line.

Air pressure is supplied to the receptacle 5 through line 13 which is provided with a valve 14 and a pressure regulator 15. In order to refill the receptacle 5 with water, it is necessary to shut off the air pressure and to vent the pressure maintained therein. Accord-

ingly, a vent line 16 is provided for this purpose having a valve 17.

A device for dosing the receptacle 5 with a chlorine or other solution is indicated generally at 20 and constitutes one embodiment of the present invention. It will be understood that in an actual installation the receptacle 5 will be many times larger than the device 20. This device 20 comprises a closed container 21 which may be in the form of an inverted bottle formed of glass or other material and having an exteriorly threaded neck 22. The mouth of the bottle 21 is closed by a diaphragm member 23 in which there is a relatively small hole 24 and a relatively larger hole or opening 25. A riser tube 26 is fitted over the larger hole 25 and projects up into the container 21 to a point adjacent the upper end thereof.

A dosage chamber or cup 27 having an indented and interiorly threaded neck 28 is screwed onto the mouth of the container 21 so that the diaphragm 23 is sealed between the rim or lip of the bottle mouth and a horizontal flange 30.

The dosage chamber 27 is provided adjacent the bottom thereof with an outlet opening or passageway 31 for receiving one end of a pipe or tube 32, the other end of which is connected through a union 34 to the top of the receptacle 5 as shown so as to open into the pressure head space 11.

The operation of the dosing device 20 is as follows, assuming that the device 20 is to be connected to the receptacle 5 which is filled with water to level 10. The valves 12 and 14 in the water and air lines, respectively, are closed and the vent valve 17 is open. The container or bottle 21 will be turned right side up and filled with a chlorine solution of proper strength, the filling being stopped short of full capacity so that when the bottle 21 is inverted as shown in Fig. 1, a freeboard space or pressure head 33 will be left at the top of the bottle. The dosage chamber 27 carrying tube 32 is screwed onto the neck 22 and the bottle 20 is turned over and the union 34 is connected. It will be noted that the capacity of the dosage chamber is many times smaller than the container or bottle 21.

In order to put water throughout the system 6, the vent valve 17 is closed and the valve 14 in the air pressure line 13 is opened. The pressure builds up in the gas space 11 and since the pressure in the gas space 33 in the container 21 was at atmospheric pressure, air under pressure in the head space 11 is transmitted through the line 32 into the dosage chamber 27 and rises through opening 25 and the riser pipe 26 blowing any liquid therein ahead of it. A fraction of the chlorine solution and air introduced under pressure into the dosage chamber 27 may pass through the smaller outlet opening 24 and this arrangement serves to clear this opening should any foreign or obstructing material become lodged therein. The pressure within the gas space 33 will increase along with the pressure in the gas space 11 until equilibrium is reached. The solution blown out of the dosage compartment 27 will leave an air bubble in the top of this chamber and this air bubble will be released through the riser pipe 26 and replaced with solution passing down through the small communicating hole 24 by gravity. In a short time after equilibrium is reached, the dosage compartment 27 and riser pipe 26 will be filled with the chlorine solution up to the chlorine liquid level which defines the bottom of the gas space 33.

The pressure on the gas space 11 is maintained by the pressure regulator 15 as the water is withdrawn to the consuming system 6 through the main 7. In the water system of a railroad car the pressure in the head space may, for example, be set at 25 pounds per square inch gauge, but is often found set at pressures ranging from 5 to 30 psig. The pressure may fluctuate somewhat on both sides of the set operating value.

When it is desired to refill the receptacle 5, the air

pressure line valve 14 is closed and the vent line valve 17 is opened so as to release the pressure in the freeboard space 11. When this pressure is released there will of necessity also be a release of the pressure in the gas space 33 in the dosing unit 20. This pressure will exert itself downwardly through the riser 26 and will force the chlorine solution in this pipe together with the solution in the dosage chamber 27 ahead of it out through the conduit 32 into the main water tank 5. In other words, the chlorine solution in the riser 26 and the dosage chamber 27 acts as a piston until the level drops to the point where the outlet opening 31 in the dosage chamber 27 is exposed, at which point the air pressure will be released rapidly after the pipe 32 has been cleared of solution which is in it. In this way the receptacle 5 is dosed with chlorine solution each time the pressure thereon is released preparatory to refilling. The dosage of chlorine solution will consist primarily of that contained in the dosage chamber 27. In addition, there will be the solution which stands in the riser 26 and in the vertical leg of the pipe connection 32. However, the internal bores of these parts are small so that the amount of solution therein is relatively insignificant in relation to the volume which is contained in the dosage chamber 27.

Since the passage 24 is small in relation to the opening 25, only a small amount of the solution will be forced through this passage or duct when the pressure is released.

After the receptacle 5 has been vented and the dosing device 20 has operated, the receptacle is refilled through the supply line 8 and then pressure is re-established by closing the vent 17 and opening the valve 14. Upon the re-application of pressure, the pressure will again build up in the gas space 33 as described above so as to be available for blowing another dose of the chlorine solution into the receptacle 5 upon the subsequent release of the pressure therein.

It will be seen that the dosing device 20 operates automatically without the necessity of any moving part. If it is desired to provide for refilling the dosing device 20 while the receptacle 5 is under pressure, a shut-off valve may be placed in line 32. The container 21 normally needs re-filling at periods from several weeks to several months, depending upon usage of the railway passenger car with which it is associated.

The system described in connection with Fig. 1 operates on a variation in pressure in the water system between atmospheric and some superatmospheric pressure such as 30 p. s. i. g. It will be appreciated, however, that the dosing device 20 will operate in a similar manner by reason of a drop or variation between any other set of pressures. For example, the dosing device 20 could be used in connection with the water system of a country home. Such water systems usually include a storage tank and an automatically controlled pump which operates to draw water from a well and maintain a supply of water in the tank under a pressure ranging between, say, from 30 to 50 p. s. i. g. It will be apparent that the dosing device 20 may be used in connection with such a receptacle so as to dose the tank with a charge of chlorine solution or other liquid dosing material every cycle when the pressure drops from the maximum to the minimum.

In Fig. 2 of the drawings a dosing device is indicated generally at 35 which forms another embodiment of the invention in which the dosage chamber is disposed within the supply container for the dosing liquid. The dosing device shown in Fig. 2 is therefore especially suited for rough handling and adverse operating conditions such as those encountered in connection with railway passenger cars. The dosing device 35 operates on the same principle as does the dosing device 20 although it does incorporate certain features not incorporated in the dosing device 20.

The dosing device 35 comprises a container 36 having a top 37. The top 37 is provided with an opening 38 which is internally threaded for receiving a filling plug 40.

which is removed when the container 36 is to be filled. Directly beneath the filling opening 38 a short filling tube 41 is provided which is secured to the underside of the top 37 and serves to limit the height to which the container 36 may be filled with treating liquid such as a chlorine solution. This insures the reservation of a free-board space or gas pressure space 42.

The top 37 is provided with a central opening which is internally threaded and indicated at 43. This threaded opening serves to receive a plug 44 which is provided with a central bore 45, the upper end of which is internally threaded for receipt of a nipple member 46 and the bottom end of which is threaded for receipt of the upper end of a tube 47. A lock nut 48 serves to lock the tube 47 in any desired position in the plug 44.

The tube 47 extends down adjacent to the bottom of the container 36 and the lower end thereof is threaded so as to pass through the threaded opening 50 in the top wall of a dosing or measuring cup or chamber 51. A lock nut 52 serves to lock the tube 47 with respect to the cup 51. The bottom end of the tube 47 should extend down adjacent the bottom of the cup 51 and the exact position may be altered and adjusted by releasing the lock nuts 48 and 52 and screwing the tube 47 in the desired direction to either raise it or lower it. If desired, only the lock nut 52 may be loosened and the cup 51 may be turned on the bottom end of the tube 47 to obtain the desired adjustment.

The dosage chamber 51 is provided adjacent the bottom thereof with a small filling or inlet hole 53, the diameter of which is small in comparison with the internal bore of a riser or vent tube 54. The vent tube 54 is secured at its bottom end into the top wall of the dosage chamber 51 and projects up into the gas space or chamber 42 to a point adjacent the underside of the top 37.

The nipple 46 may be connected to one end of the tube 55 by means of a union or coupling member 56. The tube 55 may lead to the pressure space in the top of a water supply tank such, for example, as the tank 5 in Fig. 1. For a purpose to be explained more fully below, the tube 47 is preferably provided with a small diameter vent hole 57 at some point above the high liquid level in the container 36.

In putting the dosing device in operation, the filling plug 40 is removed and chlorine solution or other dosing liquid is introduced through the opening 38 until the level reaches the bottom of the filling tube 41. The plug 40 is then replaced and the tube 55 is connected with the gas space of a water system such, for example, as the supply tank of a railway passenger car. When the pressure is built up into the water system supply tank, the pressure will communicate through the tube 55 down through the tube 47 and into the measuring cup 51 and then up through the riser tube 54 into the space 42. Much of the liquid in the cup 51 will be blown up through the riser tube 54 and a very small amount will be diffused through the small diameter hole 53 thereby clearing this hole of any particles should they become lodged therein. The pressure will build up in the head space 42 until it is equal to the pressure applied to the supply system to which the tube 55 is connected.

During average pressure fluctuation in the supply system such, for example, as in the gas space 11 of the receptacle 5 in Fig. 1, there may be a tendency for the dosing device to charge some of the solution in the measuring cup 51 over into the main supply tank. The vent 57 allows the pressure within the gas space 42 to become equalized with the pressure as it fluctuates in the gas space in the main receptacle and this prevents partial dosing during relatively slow fluctuations in pressure. When the pressure in the water system supply tank is reduced quickly, such as when it is released or vented for refilling, then the pressure in the gas space 42 in the dosing device 35 acts to empty the chlorine solution in the measuring cup 51 and discharge it into the system.

That is, the pressure in the gas space 42 empties the liquid trapped in the riser 54, and in the tube 47 as well as the liquid in the measuring cup 51 down to a level even with the bottom end of the tube 47. This measured dosage is blown out through the tubing 55 over into the main system. The internal bores of the riser 54 and the tube 47 are so small compared with the capacity of the measuring cup 51 that the variation in the liquid trapped in these tubes as the liquid level in the container 36 drops is not significant. The opening 57 is small enough so that little pressure is lost through it when there is a rapid release of pressure.

It will be understood that the dosing device 35 will function repeatedly upon the release and re-establishment of pressure in the system until the liquid level in the chamber 36 has dropped down to adjacent the top of the measuring cup 51, at which point the container 36 should be refilled.

The dosage delivered by the device 35 may be regulated by adjusting the height of the tube 47 in respect to the bottom of the measuring cup 51 since the closer the bottom of the tube 47 is brought to the bottom of the measuring cup 51 the greater will be the amount of the contents of the cup which are discharged, and conversely the higher the bottom of the tube 47 is raised from the bottom of the cup the smaller will be the amount of the contents which are discharged. In addition to this means of adjustment in the dose delivered, the measuring cup 51 may be replaced with another measuring cup of different size if desired.

By these means it is readily understood that a set calibrated dosage can be provided.

The embodiments of the invention described in connection with Figs. 1 and 2 make use of the same duct 35 or conduit means for discharge of the dose of treating liquid from the dosage chamber and for introduction of gas into the dosing device for establishing a pressure in the gas space in the top of the dosing devices. By providing a separate or independent connection leading into the gas space in the dosing devices, they may be utilized in connection with receptacles which are adapted to be completely filled with liquid on refilling and in connection with liquid systems operating entirely under a liquid pressure head without air pressure being used at all.

In Fig. 3 of the drawings the dosing device 20 is shown in connection with a water distribution system which includes a storage tank 60 adapted to supply a distribution system 61 through a header or main 62 leading from the bottom of the receptacle 60. The receptacle 60 is provided with a vent line 63 having a shut-off valve 64; a water feed line 65 provided with a shut-off valve 66; and an air line 67. The dosage chamber 27 of the dosing device 20 is connected to the receptacle 60 through a conduit 68. In order to independently introduce air pressure into the gas space in the top of the treating liquid container 21, a line 70 is connected therewith which extends from the air pressure line 67. The line 70 is provided with a check valve 71.

The air line 67 is provided with a shut-off valve 72 and a regulating valve 73. The operation of the dosing device 20 in connection with the receptacle 60 is broadly the same as that described above in connection with Fig. 1. However, in this system the receptacle 60 is adapted to be completely filled by introduction of water through the line 65 with the valve 72 being closed and the vent valve 64 open. After being thus completely refilled, the vent valve 64 is closed and the water inlet valve 66 is also closed and the air valve 72 is opened. In order to insure that no water backs up in the line 67 when the receptacle 60 is being refilled, an additional shut-off valve 74 may be provided in the air line 67.

With the valves 72 and 74 open, the air pressure builds up through the check valve 71 and builds up to the desired pressure in the gas space 33 in the container 21 so as to become in equilibrium with the air pressure applied to

the contents of the receptacle 60. When the receptacle 60 is ready for refilling, the pressure which is built up therein is vented by opening the vent valve 64, whereupon the pressure in the gas space 33 serves to charge a dose of the treating liquid contained in the dosage chamber 27 into the receptacle 60 in the manner described above in connection with Fig. 1.

In Fig. 4 of the drawings the dosing device 20 is shown interconnected with a liquid system represented by the conduit 76, this system being operated entirely by liquid pressure instead of gas pressure. The dosage chamber 27 is connected to the system 76 through a line 77, this line having a section 78 which extends above the highest liquid level reached in the container 21. The raised or elevated portion 78 is provided as a precaution to prevent siphoning of the contents of the dosing device 20 under certain conditions. The gas space 33 is provided with a connection 80 leading to a source or supply of air pressure and the line 80 is provided with a solenoid type valve 81. In normal operation the pressure in the gas space 33 will be in equilibrium with the pressure on the liquid in the system 76. When it is desired to charge a dose of the treating liquid into the system 76, the solenoid valve 81 is operated and air pressure is applied in the gas space 33 which is sufficiently in excess of the pressure in the system 76 so as to cause a dose of the treating liquid in the chamber 27 to be discharged through the line 77 into the system 76. The valve 81 is closed as soon as the dose has been discharged and the pressure equilibrium in the gas space 33 and the system 76 is again established. As a matter of convenience, the solenoid 81 may be provided with a timer type switch so as to admit the air pressure for a required amount of time, for example ten seconds and then to shut it off again.

It will be apparent that certain changes may be made in the two embodiments of the invention which have been described, and that additional embodiments of the invention may be made without departing from the spirit and scope of the invention. Accordingly, all matter described above or shown in the accompanying drawings is intended to be interpreted as illustrative and not in a limiting sense.

What I claim as new is:

1. Apparatus for dosing a fluid system with a treating liquid comprising, a closed container for holding a relatively large supply of a treating liquid, a dosage chamber of small capacity relative to said container located in gravity feed communication with said container, a small duct or passageway providing communication between the interior of said dosage chamber and the bottom of said container so as to allow liquid to run therethrough from the container into said chamber and fill the latter, conduit means providing direct communication between the top of said dosage chamber and the top of said container, and a dosage discharge conduit means connected with said dosage chamber below the top thereof.

2. Apparatus for charging doses of a treating liquid into the gas space for a liquid supply receptacle and operable in response to an increase and decrease in gas pressure within said receptacle, comprising, a container for a treating liquid and having a gas space in the top thereof, a dosage chamber of small capacity relative to said container located in gravity feed communication with said container, a small duct or passageway providing communication between the interior of said dosage chamber and the bottom of said container so as to allow liquid to run therethrough from the container into said chamber to fill the latter, means providing direct communication between the top of the dosage chamber and said gas space of said container, and means providing communication between the bottom of said dosage chamber and the gas space of said receptacle.

3. Apparatus for charging doses of a treating liquid into the gas space of a liquid supply receptacle and operable in response to an increase or decrease in gas pressure within said receptacle, comprising, a relatively

large closed container for a treating liquid, means for filling said container so as to leave a gas space in the top portion thereof, a relatively small closed dosage chamber located adjacent the bottom of said container, said dosage chamber having a small liquid inlet opening therein which communicates with said closed container and a relatively larger opening in the wall of said chamber adjacent the top thereof, means providing direct communication between said larger hole and said gas space in the top portion of said container, and means providing communication between the bottom portion of said chamber and said gas space of the liquid supply receptacle.

4. Apparatus for charging doses of a treating liquid into the gas pressure space of a liquid supply receptacle and operable in response to an increase or decrease in gas pressure within said receptacle, comprising, a closed container for a treating liquid, means for filling said container so as to leave a gas space in the top portion thereof, a closed dosage chamber located adjacent the bottom of said container, said dosage chamber having a small liquid inlet opening therein which communicates with said closed container and a relatively larger opening in the wall of said chamber adjacent the top thereof, means providing direct communication between said larger hole and said gas space in the top of said container, and a tube projecting through a hole provided therefor in the top of said chamber with the lower end terminating adjacent the bottom of said chamber and the upper end of this tube communicating with a passageway through said container, and means providing communication between this tube and the gas space of said receptacle.

5. Apparatus for charging doses of a treating liquid into the gas pressure space of a liquid supply receptacle and operable in response to an increase or decrease in pressure within said receptacle, comprising, a closed container for a treating liquid, means for filling said container so as to leave a gas space in the top portion thereof, a closed dosage chamber located adjacent the bottom of said container, said dosage chamber having a small liquid inlet opening therein which communicates with said closed container and a relatively larger opening in the wall of said chamber adjacent the top thereof, means providing direct communication between said larger hole and said gas space in the top of said container, and a tube projecting through a hole provided therefor in the top of said chamber to adjust the distance between the bottom of the tube and the bottom of the said chamber, and means providing communication between the tube and the gas space of said receptacle.

6. Apparatus for dosing a liquid storage distribution system with a treating liquid in response to variation of pressures in said system, comprising, a closed container for holding a relatively large supply of a treating liquid, means for filling said container so that there will be a gas space left above the filled liquid level, a dosage chamber for holding a relatively small amount of the treating liquid located in gravity feed communication with the liquid space of said container, a small duct or passageway providing communication between the interior of said dosage chamber and the bottom of said container so as to allow liquid to run therethrough from the container into said chamber to fill the latter, means providing direct communication between the top of the dosage chamber and said gas space of said container, and an outlet adapted to provide communication between the bottom of said dosage chamber and a gas space in liquid storage system.

7. Apparatus for dosing a liquid storage distribution system with a treating liquid in response to variation in pressures in said system, comprising, a closed container for holding a treating liquid, means for filling said container so that there will be a gas space left above the filled liquid level, a dosage chamber located in gravity

feed communication with the liquid space of said container, means providing communication between the top of the dosage chamber and gas space of said container, and tubular means providing communication between a gas space in the liquid storage distribution system and said dosage chamber wherein an end of this tubular means terminates within said chamber and is adjustable to vary its distance from the bottom of said chamber.

8. Apparatus for dosing a liquid storage distribution system with a treating liquid in response to variation of pressures in said system, comprising, a closed container for holding a treating liquid, means for filling said container so that there will be a gas space left above the filled liquid level, a dosage chamber located in gravity feed communication with the liquid space of said container, means providing communication between the top of the dosage chamber and gas space of said container, and tubular means providing communication between the bottom of said dosage chamber and a gas space in liquid storage system, wherein there is a very small by-pass from this tubular means into the gas space of the closed container.

9. Apparatus for charging doses of a treating liquid into a liquid supply reception normally maintained under pressure and operable in response to a reduction in pressure within said tank, comprising, a supply container for a treating liquid, a dosage chamber of small capacity relative to said supply container located in gravity feed relationship therewith, a duct or passageway providing communication between the bottom of said supply container and said dosage chamber, a tube communicating between the top of said dosage chamber and the top of said supply container, and a duct or passageway communicating with the bottom portion of said dosage chamber and adapted to be connected in communication with the top of said receptacle.

10. Apparatus for automatically dosing a liquid storage receptacle with a treating liquid each time the pressure in said receptacle is sufficiently lower than a pressure within said apparatus, comprising, a closed outer container for holding a supply of the treating liquid, a closed dosage chamber located within and adjacent the bottom of said container, said dosage chamber having a small liquid inlet opening which communicates with said closed container and a relatively larger opening in the wall of said chamber adjacent the top thereof, a riser tube fitting said larger opening and extending upwardly in said outer container to a point adjacent the top thereof, and duct means communicating with the bottom portion of said dosage chamber and adapted to be connected in communication with a pressure head space in the top of said receptacle.

11. Apparatus for automatically dosing a receptacle with a treating liquid in response to a differential in pressure, comprising, a closed outer container for holding a supply of the treating liquid, a closed dosage chamber disposed within and adjacent the bottom of said container, said dosage chamber having a small liquid inlet opening therein which communicates with said closed container and a relatively larger opening in the top wall of said chamber, a riser tube fitting said larger top opening and extending upwardly in said outer container to a point adjacent the top thereof, and a tube projecting through a hole provided therefor in the top of said chamber with the lower end terminating adjacent the bottom of said chamber and the upper end of said second tube communicating with a passageway through the top of said outer container.

12. Apparatus for automatically dosing a receptacle with a treating liquid each time the pressure in said tank is reduced, comprising, a closed outer container for holding a supply of the treating liquid, the top wall of said container having a filling opening closed by a removable closure member, a filling tube extending from

the bottom of said filling opening down into said container so as to limit the height to which said container can be filled through said opening, a closed dosage chamber disposed within and adjacent the bottom of said container for holding a dose of the treating liquid, said dosage chamber having a small-sized liquid inlet opening in the side wall thereof, a pair of larger openings in the top wall of said chamber, a vertical riser tube fitting into one of said larger holes and extending up to a level above the bottom end of said filling tube, and a vertical tube projecting through the second of said larger openings in the chamber with the bottom end terminating adjacent the bottom of said chamber and with the upper end communicating with a passageway extending through the top wall of said closed container.

13. The dosing apparatus called for in claim 11 wherein the bottom end of said last mentioned vertical tube and the bottom of said dosage chamber are adjustable relative to each other.

14. The dosing apparatus called for in claim 11 wherein in said top wall of said closed outer container is provided with a second opening and a plug is fitted in said opening through which said dosage chamber may be inserted and removed, said plug having a passageway extending therethrough and into which is fitted the upper end of said second mentioned vertical tube.

15. The dosing apparatus called for in claim 11 wherein in said second mentioned vertical tube is exteriorly threaded at its opposite ends so that the bottom end screws into one of said larger holes in the top wall of said dosage chamber and the upper end screws into said passageway through the top wall of said container, and lock nuts are threaded on the opposite ends of said second mentioned vertical tube so as to lock it from turning relative to said chamber and said container.

16. The apparatus called for in claim 11 wherein said second mentioned vertical tube has a relatively small pressure equalizing opening in the side at a level above the bottom end of said filling tube whereby the pressure within the head space of said closed container will be equalized with pressure fluctuations within the head space of a liquid storage tank to which said passageway in the top of said closed container may be connected.

17. Apparatus for automatically dosing a treating liquid into a receptacle each time the pressure in said receptacle is reduced, comprising, an inverted container, a dosage chamber fitting on the downwardly opening neck of said inverted container, a diaphragm closing the mouth of said container and having a small opening therein and a relatively larger opening therein, and a riser tube fitting over said larger opening and extending upwardly adjacent the top of the inverted container, said dosage chamber having a passageway in the wall thereof adjacent the bottom and adapted to be connected in communication with the pressure head space at the top of a liquid storage tank.

18. In combination with a liquid storage receptacle having a pressure head space reserved in the top thereof when said receptacle is filled, an apparatus for automatically dosing said receptacle with a treating liquid each time the pressure therein is reduced a sufficient amount comprising, a closed supply container for treating liquid, a closed dosage chamber disposed in gravity feed relationship with said closed container, a small duct or passageway providing communication between the interior of said chamber and the bottom of said container so as to allow liquid to run therethrough from the container into said chamber to fill the latter, a relatively large conduit providing communication between the top of said chamber and the top of said closed container, and a conduit providing communication between the bottom of said chamber and the head space in said storage tank.

19. In combination with a liquid storage receptacle provided with means for creating, maintaining and re-

leasing pressure in a head space reserved therein when filled; an apparatus for automatically dosing said receptacle with a treating liquid comprising, a closed outer container for holding a supply of treating liquid, a closed dosage chamber located within and adjacent the bottom of said closed container, said dosage chamber having a small liquid inlet opening in the wall thereof and a relatively larger opening in the top thereof, a riser tube fitting in said larger opening and projecting up to adjacent the top of said closed container, and a conduit communicating between the bottom of said chamber and the head space of said storage tank.

20. In combination with a water storage tank provided with means for creating, maintaining and releasing air pressure in a head space reserved in said tank when filled, an apparatus for automatically dosing said tank with chlorine solution each time the pressure in said tank is vented, comprising, a closed supply container for treating liquid, a closed dosage chamber disposed in gravity feed relationship with said closed container, a small duct or passageway providing communication between the interior of said chamber and the bottom of said container so as to allow liquid to run therethrough from the container into said chamber to fill the latter, a relatively large conduit providing communication between the top of said chamber and the top of said closed container, and a conduit providing communication between the bottom of said chamber and the head space in said storage tank.

21. In combination with a water storage tank provided with means for creating, maintaining and releasing air pressure in a head space reserved in said tank when filled with water, an apparatus for automatically dosing said tank with chlorine solution each time the pressure in said tank is vented, comprising, a closed outer con-

5 tainer for holding a supply of chlorine solution, a closed dosage chamber located within and adjacent the bottom of said closed container, said dosage chamber having a small liquid inlet opening in the wall thereof and a relatively larger opening in the top thereof, a riser tube fitting in said larger opening and projecting up to adjacent the top of said closed container, and a conduit communicating between the bottom of said chamber and the head space of said storage tank.

10 22. Apparatus for charging doses of a treating liquid into a liquid supply tank normally maintained under pressure and operable in response to a reduction in pressure within said tank, comprising, a supply container for a treating liquid, a dosage chamber of small capacity relative to said supply container located in gravity feed relationship therewith, a small duct or passageway communicating between said supply container and said dosage chamber, a tube of relatively large size compared to said small duct or passageway and communicating between the top of said dosage chamber and the top of said supply container, and a duct or passageway communicating with the bottom portion of said dosage chamber and adapted to be connected in communication with the top of said tank.
